UNITED STATES PATENT OFFICE.

MINNIE M. FARRELL, OF KANSAS CITY, MISSOURI.

DESIGN FOR A DOLL PINCUSHION.

61,153.

Specification for Design.

Patented July 4, 1922.

Application filed January 11, 1922. Serial No. 161. Term of patent 7 years.

To all whom it may concern:

Be it known that I, MINNIE M. FARRELL, a citizen of the United States, and a resident of the United States, residing at Kansas City, county of Jackson, State of Missouri, have invented a new, original, and ornamental Design for a Doll Pincushion, of which the following is a specification, reference being had to the accompanying drawing, forming a part thereof.

In the drawing:

The figure shown represents a perspective view of a doll pincushion showing my new design.

I claim:

The ornamental design for a doll pincushion, as shown.

MINNIE M. FARRELL.
